UNITED STATES PATENT OFFICE.

JOSEPH A. DEDOUCH, OF OAK PARK, ILLINOIS.

MEDALLION MOUNTING.

Application filed January 19, 1925. Serial No. 3,530.

To all whom it may concern:

Be it known that I, JOSEPH A. DEDOUCH, a citizen of the United States, residing at Oak Park, in the county of Cook and State 5 of Illinois, have invented a new and useful Improvement in Medallion Mountings, of which the following is a specification.

This invention relates to medallion mountings and the like and is particularly adapted to be used for mounting medallions, plates and other objects on monuments and other flat surfaces.

The invention is fully described in the following specification and shown in the accompanying drawing, in which:

Figure 1 is a vertical section on the line 1 of Fig. 5 showing the medallion mounted on the face of a smooth surface;

Fig. 2 is a similar view showing a tool 20 being inserted under the lower edge of the mounting to cause it to be released;

Fig. 3 is a side elevation of the releasing tool;

Fig. 4 is a section on the line 4 of Fig. 5; 25 and

Fig. 5 is a rear elevation showing the yieldable retaining member in place.

The embodiment illustrated comprises a dished elliptical medallion 10 having an inwardly extending bar or plate 11 which has a slot 12 therein which lies substantially parallel to the back of the medallion. The bar 11 is preferably substantially flush with the edges of the medallion as shown in Fig. 30 1, so as to bear upon the surface 13 to which it is to be secured, thereby acting as a support for the center dished plate.

A yieldable member 14 of spring bronze or the like, has an opening 15 at one end by 40 means of which it may be secured by a screw 16 or the like to a suspension bolt 17 of a well known type. This consists of a conical member surrounded by a jacket 18 of soft metal as lead which when forced into contact with the drilled hole 19 grips the inner surface of the hole so that any further pull 45 on the tapered sleeve 17 causes the metal jacket 18 to grip the hole 19 more firmly.

With the yieldable member 14 thus secured to the face of the monument 13, the end 20 which is preferably depending from the point of support, is slightly offset, and the lower end 21 slightly curved upward so 50 as to enable the dished plate to be passed thereover with the lower end 21 entering the slot 12. This lower end also has an inwardly

bent tongue 22 which yields to permit the portion 20 to pass through the slot, but which expands outwardly as shown in Fig. 1, thereby preventing withdrawal of the 60 same as soon as this tongue has passed through the slot 12. Shoulders 23 on each side of the member make contact with the opposite side of the bar 11 at the instant the tongue 22 passes through, thereby firmly 65 locking the bar 11 with respect to the member 14 and preventing the plate 10, to which the bar 11 is secured from swinging to any appreciable extent about the member 14.

Owing to the spring action of the member 14, the plate is held yieldingly against the surface 13 of the monument or other objects to which it is attached. Thus changes of temperature, or the accumulation of ice will not damage the device since the spring 70 member 14 is able to yield thereby preventing damage, but immediately draws the plate back against the face of the stone as soon as the force applied thereto is withdrawn.

It is sometimes desirable to remove the 75 medallion and for this purpose I have provided a tool 24 which is slidable under the lower edge of the medallion. If the tool 24 is pushed upwardly, it will pass under the outwardly curved end 21 and as it advances 80 will pass under the spring tongue 22, thereby causing it to be retracted so that the plate 10 may again be drawn down, bar 11 passing over the tongue 22. It will be understood that it is necessary to keep the tool 85 24 inserted only long enough to force the tongue 22 over the bar 11 after which the tool 24 may be withdrawn and the medallion 90 may then be drawn down and off the lower end of the yieldable member 14.

If it is desired however that the medallion shall not be removed when it is once in place, the lower end of the member 14 may be turned in the reverse direction from that shown in Fig. 2 so that it will bear against 100 the surface 13 thereby making it much more difficult to insert any tool for removing the medallion.

It will be noted that the weight of the medallion is suspended from the bolt 17 105 which lies above its center of gravity so that it will remain in substantially the same position even though the member 14 becomes loose for any reason.

While I have shown and described but a single embodiment of this invention, it is to be understood that it is capable of many 110

modifications. Changes therefore in the construction and arrangement may be made which do not depart from the spirit and scope of the invention as disclosed in the 5 appended claims.

I claim:

1. In combination, a plate having a depression on its under side, a bar secured thereto within said depression, a yieldable member adapted to pass between said bar and plate and to be fastened to a surface to which it is desired to secure said plate, and means on said member for locking said member on said bar when said member has been forced therethrough a predetermined distance.
2. In combination, a plate having a depression on its under side, a bar secured thereto within said depression, a part of 20 said bar being flush with the edges of said plate so as to provide a central support therefor, a yieldable member adapted to pass between said bar and plate and to be fastened to a surface to which it is desired to 25 secure said plate, and means on said mem-

ber for locking said member on said bar when said member has been forced therethrough a predetermined distance.

3. In combination, a plate having a depression on its under side, a bar secured thereto within said depression, a yieldable member adapted to pass between said bar and plate and to be fastened to a surface to which it is desired to secure said plate, and a spring tongue on said member for locking said member on said bar when said member has been forced therethrough a predetermined distance.

4. In combination, a plate having a depression on its under side, a bar secured thereto within said depression, a yieldable member adapted to pass between said bar and plate, means above the center of gravity of said plate for fastening said member to a surface to which it is desired to secure said plate, and means on said member for locking said member on said bar when said member has been forced therethrough a predetermined distance.

JOSEPH A. DEDOUCH.
